UNITED STATES PATENT OFFICE

GEORGE H. DAWSON, OF BOSTON, MASSACHUSETTS, ASSIGNOR TO SERVICE BUREAU, INC., OF CAMBRIDGE, MASSACHUSETTS, A CORPORATION OF MASSACHUSETTS

VISIBLE STRIP INDEX

Application filed June 25, 1928. Serial No. 287,993.

This invention relates to index devices and particularly to indexes of the so-called visible type wherein a series of cards or strips are assembled in overlapping relation with their respective margins exposed to display names or other identifying subject matter. The invention has to do particularly with the construction and arrangement of the index strips and its principal object is to provide a simple and unique index of this type comprising a series of interlocked, overlapping strips adapted to display typed, printed or written index data along the entire width of the exposed strip margins and to constitute an interconnected assemblage which may readily be carried about as an individual composite sheet or which may be filed in a drawer or attached upon a vertical support for ready reference. Other more specific objects reside in the details of structure hereinafter described and pointed out in the appended claims.

Recommended embodiments of the invention are illustrated in the accompanying drawings, in which:

Fig. 1 is a front elevation, partially broken away, of one form of the improved index showing a series of interconnected index strips, each of single thickness, mounted within a folder;

Fig. 2 is a face view of an individual index strip forming part of the index of Fig. 1;

Fig. 3 is a view similar to Fig. 1 with the folder omitted, the top strip being protected by a transparent sheath and the bottom strips being swung upwardly to permit inscriptions to be made on the normally concealed portion of one of the strips;

Fig. 4 is a face view of a portion of a continuous blank or sheet from which double thickness index strips may be prepared;

Fig. 5 is a rear view of the sheet of Fig. 4;

Fig. 6 is a face view of a folded index strip made from said continuous sheet; and

Fig. 7 illustrates an assemblage of several of the strips of Fig. 6.

The individual index strips forming part of the improved index may be made of any suitably flexible sheet-material such as card-board or heavy paper and may be of any de-

sired length and width. Each strip has one or more tongues or tabs and one or more corresponding slots or apertures whereby, when the strips are detachably interconnected to form the assembled index, the tongue or tongues of one strip are removably received and retained within the complementary slot or slots of the adjacent strip of the series, thereby to interlock and space the strips relatively to one another with their margins projecting one beyond another.

A pair of tongues having their bases in the same line and substantially parallel to one longitudinal edge of the strip and having their ends projecting in opposite directions are preferably provided near the respective ends of each strip and these tongues are preferably inserted into corresponding slots in the next adjacent strip by flexing the strip transversely so that, when the strip is released, the projecting ends of the tongues extend beyond the outer ends of the respective slots effectively to interlock the strips against casual displacement. The strips may be tilted or swung upon the hinge-joint thus formed, yet the units are so interconnected that the assembled composite sheet index is self-sustaining without the necessity of providing expensive metal frames or other index holders.

Each of the strips 10 illustrated in Figs. 1 to 3 consists of a single thickness of card-board and has a pair of tongues 11 projecting from its upper edge and a pair of apertures or slots 12 disposed below said tongues and substantially parallel to said upper edge. The tongues have outwardly projecting ends 13 which lock behind the strip next above at the outer ends of the respective slots thereof, when the strips are assembled as aforesaid in overlapping relation. As thus arranged the upper margin of each strip is exposed to display names or other data appearing thereon, and it will be observed that the typing or printing may be carried to the extreme ends of said margins. Furthermore, it will be apparent, as indicated in Fig. 3, that the normally concealed lower portion of any of the strips may be exposed for inspection or entries by swinging upwardly the strip or

80

95

100

group of strips disposed below the strip to be disclosed.

In Fig. 1, the assembled index is removably attached within a folder 14 which may have a transparent reinforcing sheet 15 cemented upon the upper margin of its rear leaf and having a pair of slots 16 adapted to receive the tongues 11 of the topmost strip of the series. The sheet 15 which serves as a backing for said strip may also have a pocket 10 for a removable label, as shown in the drawing.

Fig. 3 illustrates another form of backing or sheath which may be opaque or transparent, comprising a folded sheet providing a front flap 25 and a rear flap 26, the front flap having slots 27 to receive the tongues 11 of the strips 10; and shows the three bottom strips in the series swung upwardly upon the hinge to permit inspection of or the making of notations upon the lower, normally concealed portion 10^a of the fourth strip from the bottom. Obviously the concealed portion of any selected strip may be thus quickly and easily exposed without disturbing the arrangement of the interlocked strips. When the upturned strips are released they will fall back into normal position without manual adjustment.

The modified form of index illustrated in Figs. 4 to 7 comprises a series of double thickness unit strips 18 each consisting of a strip of paper folded along its central longitudinal line to provide a pair of similar leaves which are preferably united to each other along their lower edges by a suitable adhesive. Downwardly extending tongues 19, similar in their essential characteristics to the tongues 11 of the strips 10, are stamped out or cut from the body of the front leaf of each strip and are adapted to interlock with corresponding slots 20 provided at the upper folded edge of the strip next below in the series. The bases of the respective tongues 19 are preferably spaced below and parallel to said folded edge, so that in the resulting assemblage (Fig. 7) the upper margins of the interconnected, overlapping strips are exposed and the strips may be swung on the hinge-joint as above described.

The strips 18 may be conveniently formed without loss of material from a continuous paper sheet stamped out and perforated as shown in Figs. 4 and 5. Suitable lines may be printed on the sheet to indicate the fold line 21 and the margin line 22 so that the margins may be typed before the individual strips are separated upon the perforations 23. The rear face of the sheet is preferably gummed as indicated at 24 (Fig. 5) along one or both sides of the perforations 23, whereby the bottom margins of the detached folded strips may be quickly and easily joined together by moistening the adhesive area.

When the doubled strips 18 are assembled

in interconnected relation (Fig. 7), a selected number of the strips may be swung outwardly on the hinge-joints formed by the interlocked tongues and grooves, to expose the normally concealed lower face portion of an underlying strip as in the case of the uni-ply strips of Figs. 1 to 3; for the yielding paper tongues 19 may readily be flexed transversely without causing permanent deformation of the tongues. Furthermore, in the folded strips, as in the flat strips of single thickness, informative notations may be typed or written upon the exposed margin of the strip, and the typing may be carried to the lateral edges thereof. It will be noted that the said exposed margin is located between a line passing through the bases of the tongues and a line extending through the slots of the respective strips, in both species of this invention. Each of these structural features constitutes an important result of the present invention, and it is believed, a radical departure and desirable improvement in visible indexes of the simple and inexpensive type is herein provided.

Although the arrangement of the indexes herein illustrated and described provides an exposed margin along the top of each strip, it is obvious that the assembly may be reversed end for end in use so that the exposed margins appear at the bottom of the individual strips. Other arrangements may be employed and structural details may be varied in order to adapt the index to a variety of uses without departing from the essence of this invention as defined in the appended claims. The assembled strip index may be filed or transported in an envelope, folder or tray with or without a backing or other reinforcement; it may be fastened upon an upright display board or other support; or it may be mounted upon a relatively stiff backing as shown in Figs. 1 and 3.

I claim:

1. A visible index comprising a series of overlapping strips, each having a tongue and a slot adapted to receive and retain the tongue of the next adjacent strip, whereby the strips are detachably interconnected and are spaced by said tongues and slots relatively to one another with their margins projecting one beyond another, the tongue and slot connection constituting a hinge-joint upon which one of two adjacent strips may be swung outwardly.

2. A visible index comprising a series of overlapping strips, each having a pair of tongues and a pair of corresponding slots adapted to receive the tongues of the next adjacent strip, the tongues of each pair having their bases in line and their respective ends projecting laterally in opposite directions to interlock with said slots, the tongues and slots extending substantially parallel to the longitudinal edges of the respective

strips, whereby the strips are detachably interconnected and are spaced by said tongues and slots relatively to one another with their margins projecting one beyond another, the tongue and slot connection constituting a hinge-joint upon which one of two adjacent strips may be swung outwardly.

- 5 3. A visible index comprising a series of overlapping strips, each having a pair of 10 tongues arranged with their bases in the same line and parallel to one edge of the strip and each having a pair of slots disposed substantially parallel to said edge and in line with each other, the tongues of each 15 pair having their respective ends projecting in opposite directions thereby to interlock with the corresponding slots of the next adjacent strip, so that the strips are detachably interconnected and are spaced by said tongues 20 and slots relatively to one another with their margins projecting one beyond another.

4. A visible index comprising a series of overlapping strips, each having a pair of tongues and a pair of corresponding slots 25 adapted to receive the tongues of the next adjacent strip, the tongues of each pair having their bases in line and their respective ends projecting laterally in opposite directions to interlock with said slots, the tongues 30 and slots extending substantially parallel to the longitudinal edges of the respective strips, whereby the strips are detachably interconnected and are spaced by said tongues and slots relatively to one another with their 35 margins projecting one beyond another, the tongue-and-slot connection constituting a hinge-joint upon which one of two adjacent strips may be swung outwardly, and a backing sheet having a pair of slots adapted to receive the tongues of the topmost strip in the 40 series.

5. A visible index comprising a series of substantially flat strips arranged in overlapping relation, each strip having a pair 45 of tongues disposed with their bases in the same line and parallel to one edge of the strip and each having a pair of slots substantially parallel to said edge and in line with each other, the tongues of each strip having their ends projecting in opposite directions to interlock with the corresponding slots of the next adjacent strip, so that the strips are detachably interconnected and are spaced by said connections relatively to 50 one another with a margin of each strip located between the line of the tongues and the line of the slots in said strip exposed to view.

6. A visible index comprising a series of substantially plane, single-ply strips arranged in overlapping relation, each strip having a pair of tongues projecting beyond one edge thereof, the ends of the tongues extending in opposite directions, and having a pair of slots receiving and interlocking 55 with the tongues of the next adjacent strip,

said slots being spaced in line substantially parallel to said tongued edge and remote from the opposite edge of the strip, whereby the margin of each strip lying between said tongued edge and said aligned slots is exposed to view in the assembled index.

Signed by me at Boston, Massachusetts, this 15th day of June, 1928.

GEORGE H. DAWSON.
